CRACKING OF HEAVY OIL VAPORS

Emil Hene, London W.11, England

No Drawing. Application March 25, 1941, Serial
No. 385,148. In Great Britain February 14,
1940.

9 Claims. (Cl. 196—63)

This invention relates to improvements in and relating to the treatment of heavy oil vapors and it relates more particularly to processes for cracking such vapors at high temperatures and in iron vessels.

In cracking operations it is often desirable to produce a maximum of hydrocarbons higher than propylene, the production of butylene and iso-butylene being particularly desirable, whilst the formation of carbon and asphaltic materials should be avoided.

Now it has been stated in literature that heavy paraffinic oil vapors can be cracked without carbon formation at high temperatures in iron vessels coated with iron oxides, provided the reaction is carried out in the presence of steam, and the minimum proportions of steam which have been mentioned are quite considerable.

An investigation of the behaviour of heavy oil vapors when treated in iron vessels having an oxidised surface, at high temperatures in the presence of quantities of water of the order mentioned in the literature, say from 6%—10% by weight of the charging stock has shown that the process when carried out under these conditions results in large quantities of ethylene and propylene whilst only small quantities of liquid hydrocarbons (gasolene) and olefins higher than propylene are formed. Further investigations have shown that by suitably modifying the process referred to, and carefully controlling the conditions under which it is carried out, greatly improved results of great industrial utility can be obtained.

It is to the results of these further investigations, to be herein described, that the present invention relates.

It should be stated that the oils used for the investigations were heavy oils, the I. B. P. (initial boiling points) of which were higher than 300° C. and that the cracking temperatures used were above 600° C. The present invention therefore relates mainly, but not necessarily exclusively, to such oils.

It was found that when used under these conditions water vapor exerts two separate and quite distinct effects. Firstly—it has an oxidising effect on the iron so that any iron formed by the reduction of iron oxide on the vessel by carbon produced during the reaction is immediately re-oxidised. Secondly—it has a diluting effect, which although of considerable importance must be confined within certain comparatively narrow limits. If the dilution is insufficient there is a tendency for asphaltic substances to be formed from some of the heavy molecules, probably by polymerisation, thus leading to the formation of more carbon than can satisfactorily be disposed of by the iron oxide. If on the other hand the dilution is too great, the splitting of the molecules

or cracking is too drastic, leading to the formation of compounds, e. g. ethylene, containing too few carbon atoms.

It was further found that this dilution effect can be equally well, and in some respects even better achieved by gases or vapors other than water, such as for example, hydrocarbons which have little tendency to produce carbon under the conditions of the reaction.

As a result of these observations it was found that provided the heavy oil vapors were appropriately diluted with a suitable non-aqueous, and preferably hydrocarbon diluent the amount of water vapor required for purposes of oxidation was much less than had hitherto been thought necessary. Thus, for example, it was found that when a small percentage of gasolene or gas oil was mixed with the heavy charging stock an addition of only 0.5% or less of water was sufficient to give good results.

The effect of these observations will be apparent from the following explanation. It can easily be calculated that in a mixed vapor containing 6% by weight of water vapor and 94% by weight of the vapor of an oil of a molecular weight of about 300 the volume of the aqueous diluent is about 50% of the total volume, whilst in the case of an addition of only 0.5% weight of water the volume dilution is about 7.5%.

Whilst then the presence of water vapor is desirable in order to ensure the necessary oxidation effect, it has been found that the equally necessary dilution effect can be better produced and controlled within the necessary limits by the employment of a suitable non-aqueous diluent inert as to capability of functioning as an oxidizer and preferably hydrocarbon diluent vapor.

As a result of all these investigations it has been found, according to the present invention, that heavy oil vapors of an I. B. P. higher than 300° C. can be cracked at temperatures above 600° C. in iron vessels coated with iron oxide provided that at the moment of their entry into the cracking plant the heavy oil vapors are diluted with a relatively small volume of an inert vaporous or gaseous diluent, preferably a hydrocarbon, and containing a small volume of one or more gaseous oxidising agents, preferably water vapor.

It is, of course, preferred to use as a diluent a hydrocarbon which, under the conditions of the reaction will undergo a favourable change; thus for example, ethylene will produce propylene and higher olefins whilst light paraffins tend to produce higher olefins.

The reaction mixture is preferably so constituted that at the moment of their entry into the plant the heavy oil vapors are of at least twice the volume of the diluent, which latter preferably consists of water vapor and one or more other

inert, vaporous or gaseous diluents, preferably as stated above of a hydrocarbon nature, the water vapor being always present in a volume less than that of such other diluent.

In practice it is found that the added water vapor should be less than 1% by weight of the charging stock, an addition of 0.5% or less being generally found sufficient. The temperature for the production of gasoline and potential gasoline of high value from heavy oils of an I. B. P. of 300° C. or above is always above 600° C. and generally lies between 600° and 700° C., the preferred temperature being between 650° and 680° C.

It will be understood that the optimum conditions of temperature and of the nature and amount of diluent and oxidizing gases or vapors to be added will depend on various circumstances, mainly of course on the characteristics of the charging stock, and to some extent on the nature of the cracked material which it is desired to produce. These conditions will be easily ascertainable by a few relatively simple experiments. The following examples are given by way of illustration only and to facilitate a complete understanding of the invention:

Examples

The vapors from a heavy distillate oil (I. B. P. above 300° C.) were treated at substantially atmospheric pressure by being passed through a slightly oxidized iron tube 10 inches long and of 1 inch diameter at temperatures between 660° and 680° C., and in the presence of water vapor in an amount of approximately 0.5% by weight of the oil treated. In Example I no other diluent was used.

Example I.—100 ml. of the mixed vapors were passed through the tube at a rate of 2 ml. per minute. Carbon formation was observed and aromatic tarry matter was produced.

Example II.—The same experiment was carried out, but on this occasion 3 litres of ethylene were simultaneously passed through the tube.

No carbon was observed and no aromatic or tarry matter was produced. The only reaction which occurred was a cracking into paraffins of a molecular weight lower than that of the charging stock, olefins and a small quantity of hydrogen.

Example III.—The same oil as used in the previous two examples, and containing the same amount of water vapor was employed, but instead of diluting the vapors with ethylene, 5% by weight of gasoline and 5% of light gas oil from the original crude oil stock was used. The results obtained were similar to those of Example II.

It should be noted that owing to the tendency for undesired reactions to occur at temperatures below the optimum, it is essential that the mixture to be treated, reach the reaction temperature as rapidly as possible and that the heat required for the reaction be supplied in the shortest possible time. The attainment of this desirable object is facilitated according to the present invention by the reduced amount of water vapor employed. A high proportion of water vapor tends to increase the thickness of the iron oxide coating on the tube or vessel which tends to impede the rapid transfer of heat, without increasing the protection of the coating.

In the foregoing I have explained some of the

theoretical considerations on which my invention is based. Whilst I believe these considerations to be correct, I desire to state that the invention, which consists of the improved process as described, is not limited by any theoretical consideration or explanations.

I claim:

1. A process of cracking vapors of heavy oil comprising diluting said vapors with lighter vaporous or gaseous non-aqueous diluent material inert as to capability of functioning as an oxidizer in the process and with vaporous or gaseous oxidizer material in a combined or total volume of diluent and oxidizer material not more than half the volume of said heavy oil vapors and in a volume for the oxidizer material less than the volume of the diluent material, and subjecting said thus diluted heavy oil vapors to cracking conditions of temperature and pressure in a reaction chamber having its interior contact surface coated with iron oxide.

2. A process of cracking vapors of heavy oil as defined in claim 1 and in which said oxidizer material comprises water vapor.

3. A process of cracking vapors of heavy oil as defined in claim 1 and in which said diluent material comprises a lighter vaporous or gaseous hydrocarbon than said heavy oil vapors.

4. A process of cracking vapors of heavy oil as defined in claim 1 and in which said diluent material comprises a hydrocarbon productive of an olefin of greater number of carbon atoms than said diluent hydrocarbon under said cracking conditions of temperature and pressure to which said heavy oil vapors are subjected.

5. A process of cracking vapors of heavy oil as defined in claim 1 and in which said diluent material comprises a lighter vaporous or gaseous hydrocarbon than said heavy oil vapors and water vapor is employed as said oxidizer material.

6. A process of cracking vapors of a heavy oil comprising diluting said vapors with lighter vaporous or gaseous non-aqueous diluent material inert as to capability of functioning as an oxidizer in the process in a weight amount for said diluent material of not more than 10 per cent of the weight of the heavy oil charge from which said heavy oil vapors were formed and with vaporous or gaseous oxidizer material in a weight amount less than 1 per cent of the weight of said heavy oil charge and subjecting said thus diluted heavy oil vapors to cracking conditions of temperature and pressure in a reaction chamber having its interior contact surface coated with iron oxide.

7. A process of cracking vapors of a heavy oil as defined in claim 6 and in which water vapor is employed as said oxidizer material.

8. A process of cracking vapors of a heavy oil as defined in claim 6 and in which said diluent material comprises a lighter vaporous or gaseous hydrocarbon than said heavy oil vapors and water vapor is employed as said oxidizer material.

9. A process of cracking vapors of a heavy oil as defined in claim 6 and in which the heavy oil from which said vapors are formed is one having an initial boiling point of not less than 300° C. and in which a temperature of not less than 600° C. is employed for the cracking of said heavy oil vapors.
